Annelie Strasburger INVENTOR

BY Bullova & Bullova ATTORNEYS

UNITED STATES PATENT OFFICE.

AMELIA STRASBURGER, OF NEW YORK, N. Y.

GAME APPARATUS.

1,345,277.

Specification of Letters Patent. Patented June 29, 1920.

Application filed January 4, 1918. Serial No. 210,357.

To all whom it may concern:

Be it known that I, AMELIA STRASBURGER, citizen of the United States, and resident of No. 241 W. 101st street, in the borough of 5 Manhattan, city of New York, county of New York, and State of New York, have invented certain new and useful Game Apparatus, of which the following is a specification.

10 This invention relates to game apparatus and particularly to game apparatus which is educational in its character as well as adapted for amusement purposes.

The main object of the invention is to 15 provide an apparatus which makes necessary the use of arithmetical calculations in playing games adaptable to it. Another object is the production of an apparatus of this class which is of low cost, and adapted 20 for the use of small or large parties of players.

The apparatus of my present invention embodies a plurality of members which I term playing pieces, which may bear devices, 25 such as characters, symbols or representations, representing numbers, and which devices, characters, symbols or representations may be formed in any suitable manner such as numbers in Arabic notation, or the like. 30 These pieces are played in conjunction with what I term a master piece or master game piece or pieces, which piece or pieces may also be provided with devices such as characters or representations representing numbers 35 that bear arithmetical relations to the devices, characters or representations on the before-mentioned playing pieces, such as products or sums of those characters, representations or numbers.

40 In the production of the various parts of my improved game apparatus, I have found it very advantageous to make them of thin flat material such as paper board or the like, and to print, impress or otherwise form the characters, representations or numbers thereon. 45 With this construction I sometimes term the members respectively master cards and playing cards.

In the drawing accompanying and forming part of this specification I have illustrated means for carrying out the above-mentioned object, together with other features of my invention not hereinbefore described and which will be fully brought out 55 as the description progresses.

Figure 1 of the drawing is a face or plan view of one of the master game pieces or cards.

Fig. 2 is a face or plan view of the opposite side of the same master game piece or 60 card.

Figs. 3 and 4 are face or plan views of other master pieces or master cards.

Fig. 5 illustrates a few of the playing pieces or cards adapted to be used with master pieces or cards such as those illustrated in Figs. 1 to 4 inclusive.

Fig. 6 is a diagram illustrative of modes of using my present invention in playing 70 games.

Like reference characters refer to like parts in all figures of the drawing.

In all the figures of the drawing the master game pieces or cards are designated by the letter A, and the playing pieces or cards 75 by the letter B. Referring to Figs. 1 to 4 inclusive, it will be noted that the master pieces or cards are provided with characters on their faces, such as 16, 30, 72, 24, etc., and I have designated such master card 80 characters or numbers by the letter C. I preferably employ Arabic numerals for these characters. For convenience in using the master cards with the other cards that make up a set, I make the cards A polygonal 85 in shape, so that the sides D of the polygons shall form straight edges against which the edges of the playing pieces or cards can be set. I also divide the surfaces of the master cards into spaces, as by means of radial 90 lines such as E, and place one of the characters or numbers C in each space. These spaces may or may not be colored, but it is provided that when the spaces are arranged in different colors that this feature may influence the playing of the games. In Figs. 1 95 and 3, I have indicated conventionally how the master game pieces may be colored, and in Fig. 5 I have indicated how the playing pieces may be colored, also conventionally. 100

As hereinbefore noted each of these pieces is indicated by B, and each is provided with one or more devices such as characters, representations or numbers which I designate by F, which characters or devices can be 105 arranged in various ways, such as, one in the center of a card or piece, one on each of the four corners when there are four characters and the card is rectangular, and in other ways as desired, some of which are 110

illustrated in the figure of the drawing referred to. The characters or numbers F bear arithmetical relations to the characters or numbers on the master pieces, as for instance, the left hand card of Fig. 5 bears the characters 8, 8, which by addition can be matched with 16 on the master card of Fig. 1. The arithmetical relation might be expressed in a multiplication form by reading it two times 8. The playing pieces or cards are preferably rectangular in form, so that their edges can be set squarely against the sides D of the master pieces or cards A. When the cards B are colored, usually only 10 a single color is employed on a card, and colors and numbers are so arranged that a color and combination of numbers on a B card are matched to a space of the same color on an A card when the number in that 15 space bears the proper arithmetical relation to the number or numbers or devices on the B card, such relation being the product, sum or other result determined upon. The color feature may determine the scoring, as for 20 instance, if a red card is drawn whose numbers result in 16 and two master cards bear the number 16 but only one has it in a red space, then the latter will score. 25

Various modes of playing games with this 30 apparatus are possible and one of these will now be described and is as follows:

Several persons are to play and each takes a master card A, placing it on the table before him. The object of the game is to determine who will be first to complete the 35 master card or to gain a certain number of points—say twenty-five. The dealer shuffles and places the playing cards B face downward on the table, takes up the top 40 card and reads the characters or numbers on it, as for example he reads the left hand card in Fig. 5 as two eights, or twice 8. The person having 16 on his master card calls this number, receives the card B, places it 45 in position against his master card, and scores one or such number as shall be arranged for. If two persons have 16 on their master cards, the person first to call correctly gets the card, or the one matching 50 the B card in both color and number may receive it in the manner hereinbefore mentioned.

Fig. 6 illustrates some of the ways of matching the cards, and they will be obvious 55 without further detailed description than the foregoing. From this also, it will be clear that there are various other modes of using the cards to play games, all of which are fully within the scope of my invention.

60 In carrying out the invention, details of the same may be varied from those shown, and yet the essence of the invention be retained; some features might be employed without others and new features thereof 65 might be combined with elements old in the

art in diverse ways although the herein described type is regarded as embodying substantial improvements over such modifications.

As many changes could be made with the 70 above apparatus, and many apparently widely different embodiments of the invention could be made without departing from the scope thereof, it is intended that all the matter contained in the above description 75 or shown in the accompanying drawing shall be interpreted in an illustrative and not in a limiting sense.

It is furthermore desired to be understood that the language used in the following 80 claims is intended to cover all the generic and specific features of the invention herein described, and all statements of the scope of the invention which as a matter of language might be said to fall therebetween. 85

What I claim is:—

1. A game apparatus comprising a master game piece provided with a series of devices representing nonconsecutive numbers, and a plurality of playing pieces each provided with one or more devices, the arithmetical result of the devices on any playing piece being equal to a number represented on the game piece. 90

2. A game apparatus comprising a plurality of master game pieces each provided with a different series of devices representing different nonconsecutive numbers, and a plurality of playing pieces each of which is also provided with one or more of the beforementioned devices, the arithmetical result of the said devices on any playing piece being equal to a number represented on one of the master game pieces. 95

3. A game apparatus comprising a master card provided with a series of numbers or devices, and a plurality of playing cards each provided with one or more nonconsecutive numbers or devices, the arithmetical result of the numbers or devices on any playing card being equal to one of the numbers represented on the master card. 105

4. A game apparatus comprising a plurality of master cards each provided with a series of nonconsecutive numbers or devices representing nonconsecutive numbers, one or more of which series is or are different from the others, and a plurality of playing cards each provided with one or more numbers or devices, the arithmetical result of the numbers or devices on any playing card being equal to one of the numbers represented on a master card. 110

5. A game apparatus comprising a master card provided with a plurality of spaces of different colors and different numbers in different spaces, and a plurality of playing cards of colors corresponding to the colors of the spaces on the master card and each playing card provided with one or more 120

numbers whose arithmetical result equals a number on a space of the same color on the master card.

6. A game apparatus comprising a plurality of master cards each provided with spaces and numbers, one in each space, and a plurality of playing cards each provided with one or more numbers whose arithmetical result is equal to a number represented 35 on a master card.

7. A game apparatus comprising a plurality of polygonal master cards each provided with a series of factorable numbers and a plurality of rectangular playing cards 40 15 each provided with one or more numbers which are factors of numbers on a master card whose arithmetical result equals a number represented on a master card.

8. A game apparatus comprising a plurality of polygonal master cards each divided 45 radially into spaces and bearing a series of numbers, one number in each space, and a plurality of rectangular playing cards each provided with one or more numbers, the 50 25 arithmetical result of the numbers on any playing card being equal to one of the numbers on a master card.

9. A game apparatus comprising a plurality of polygonal master cards each divided 55 radially into spaces of different colors and each space having a number and a plurality of playing cards of different colors corresponding to those of the spaces of the master 60 cards and each provided with one or more

numbers the arithmetical result of the numbers on any playing card being equal to one of the numbers represented on a master card.

10. A game apparatus comprising a plurality of master cards each provided with a series of numbers, and a plurality of playing cards each provided with one or more numbers whose sum or product equals a number 40 on a master card.

11. A game apparatus comprising a plurality of master cards each provided with spaces and numbers, one number in each space, and a plurality of playing cards each provided with one or more numbers whose sum is equal to a number on a master card. 45

12. A game apparatus comprising a plurality of polygonal master cards each divided radially into spaces of different colors and each bearing a series of numbers, one number in each space, and a plurality of 55 rectangular playing cards of different colors corresponding to those of the spaces of the master cards and each provided with one or more numbers, the sum of the numbers on any playing card being equal to a number 60 on a master card.

Signed at the city of New York, in the county of New York and State of New York, this 26th day of December, 1917.
